GAS BURNER

Earl C. Jackson, Detroit, Mich.

Application December 23, 1953, Serial No. 399,985

2 Claims. (Cl. 158—99)

2

pair in a minimum of time and with a minimum of effort.

Further objects and advantages of the invention will be apparent from the following description taken in conjunction with the drawing, wherein:

5 Fig. 1 is a perspective view of the burner as applied to a vertical wall of a furnace with only a portion of the furnace shown and parts broken away for clarity;

Fig. 2, a sectional view taken on line 2—2 of Fig. 1;

10 Fig. 3, a sectional view taken substantially on line 3—3 of Fig. 2;

Fig. 4, a top plan view of the burner showing the location of the pilot light forming structure; and

15 Fig. 5, a fragmentary inner end view of the burner.

Referring more particularly to the drawing, a portion 20 of a wall 10 of a furnace or incinerator is provided with an opening 11 through which a burner nozzle 12 extends into the furnace. Such nozzle includes a restricted Venturi portion 13 provided with a generally rectangular flange 14 extending laterally of the axis of the nozzle 12 and suitable fastening screws 15 passing through openings 25 in the flange 14 being threaded into the furnace main- 30 tain the nozzle in fixed position so that flange 14 substantially seals the burner receiver opening 11 of the furnace wall 10.

25 A portion 16 of nozzle 12 flares from the Venturi 13 toward the inner end where a conveyor wall is provided with a restricted gas and air port 17 from which the flame projects. The size of the port 17 can be increased to 30 provide for a greater flow of gas and a resulting higher rate of combustion. From the Venturi 13 a portion of the nozzle flares outwardly providing a funnel shaped portion 18 provided with an outer end wall 19 provided with air supply sector shaped openings 20. Controlled by a plate 21 having sector shaped openings 22 for registry 35 with openings 20 for adjusting the amount of air going into the burner.

40 Another object of the invention is to provide a gas burner which may be applied directly to an incinerator so the gas burner serves to completely close the opening in the furnace or incinerator whereby no other closure or sealing means is necessary.

45 A further object is to provide a one piece burner unit which may be inexpensively constructed and remain operative for a great length of time with a minimum of maintenance or repair.

50 The burner unit of the present invention includes a tubular burner nozzle having a Venturi intermediate its ends and a flaring portion at its inner end provided with a restricted opening from which the mixture of gas and air is projected and at which restricted opening, the combustion occurs. A laterally extending flange intermediate the ends of the nozzle projects a sufficient distance to 55 close the opening through which the inner end of the nozzle projects into a furnace or incinerator with the flange serving to substantially close and seal such opening. On the opposite or exposed end of the nozzle a more or less conventional funnel shaped air inlet is provided through which the air supply is controlled by an adjustable plate having apertures designed for registry with apertures in the outer or exposed end of the burner body.

60 A pilot light forming structure is provided for directing an ignition flame toward the restricted opening of the nozzle. The gas supply and control conduits to the pilot light pass through the same opening in the wall of the furnace whereby the entire burner and pilot light forming structure may be removed as a unit. A time control for limiting the flow of gas to the burner is provided and a shut off control under the influence of the heat of the pilot light flame is provided for shutting off the entire supply of gas in the event the pilot flame becomes extinguished, and a manual shut off valve in the supply line joined to the burner by a union connection permits the entire assembly to be removed for replacement or re-

65 Referring to Figs. 1 and 4, it will be noted that a laterally projecting lug 26 is cast on the side of the nozzle 12 and a bracket 27 fixed by means of screws 28 threaded into the lug 26 supports pilot light forming means 29 for providing an ignition flame for the burner projecting the flame laterally therefrom toward the restricted opening 17 at the inner end of the nozzle. Gas is supplied to the pilot light by means of conduit 30 connected by means of a union fitting to a pipe 31 upon which a control valve having a fire screen 32 rotatably secured to a knurled adjusted nut 33 are mounted. The pipe 31 has one or more openings within the fire screen 32 in communication with the pilot light forming means 29 supplying the desired amount of air for such pilot light. The amount of gas supplied to the pilot light is controlled by a removable jet mounted within the pipe 31. For locking the air supply adjustment, the fire screen 32 and knurled nut 33 are threaded on to the pipe 31 so that a binding action results when relative rotation between the fire screen and the knurled nut occurs. The fire screen and nut cover the air supply opening and the adjustment of nut 33 controls the air flow. A control tube 35 extends from the pilot light to a shut off valve hereinafter described.

70 Gas is supplied from a conventional supply pipe 36 to a manually operated shut off valve 37 of well known type and through a union connection 38 including the necessary nipples to a pilot light controlled shut off valve device 39. The pilot light control device 39 is of con-

ventional construction being provided with a reset button 40 and controlled by means of the control line 35 which extends to the pilot light and is actuated by the presence of heat due to the pilot light being ignited so that in the event the pilot light becomes extinguished, the control device 39 will automatically shut off the supply of gas.

The gas is conducted from the pilot light controlled valve device 39 through suitable conduits including an elbow 41 to a time control valve 42 which may be manually set by means of a handle 43 for maintaining the valve 42 open for a desired length of time for incinerating the material placed in the furnace. From the time control valve 42, the gas is conducted by means of a nipple 44 and a union 45 to the elbow 23 and into the orifice 46 in the end of threaded portion 24. It will be evident that the flange 14 is provided with a recess 47 for accommodating the pilot light gas supply pipe 30 and pilot light control duct 35 and the opening 11 in the wall 10 of the furnace is of sufficient size to permit complete withdrawal of the inner end of the nozzle including the pilot light forming means 29 and the supporting bracket and lug therefor whereby the entire burner with the additional structure thereon may be removed.

The installation of the burner is a simple matter of providing gas fitting connections and in the event that some portions of the control become defective and it is urgent that the incinerator or furnace be kept in operation, the shut off valve 37 may be closed, the four attaching screws 15 may be removed, and the union connection 38 separated, whereby the burner may be removed with the entire control mechanism. Any necessary adjustments can be made very simply or the entire burner and control unit may be replaced with new or rebuilt unit thereby keeping the furnace or incinerator in practically continuous operation.

The burner nozzle 12 may be removed separately by disconnecting union 45, disconnecting a union type connection 47 to the pilot light and a union type connection 48 between the control duct 35 and the pilot light controlled device 39, thereby the burner may be removed without disturbing the other control elements in the event that the burner becomes clogged or otherwise requires attention.

The burner shown operates satisfactorily for an output of 15,000 B. t. u. with the port 17 being cast therein without subsequent machining. For higher outputs the port 17 may be machined to a larger size and the controls for correspondingly increased gas consumption may be provided so that the burner may operate at any output up to 125,000 B. t. u.

It will be obvious to those skilled in the art that various changes may be made in the invention without departing from the spirit or scope thereof and therefore the invention is not limited by that which is illustrated in the drawing and described in the specification, but only as indicated in the accompanying claims.

What is claimed is:

1. A burner unit for application to a furnace comprising a tubular nozzle including an inner end having a restricted discharge opening, an intermediate portion 60 of the nozzle having a restricted cross-sectional shape

and the outer end portion of the nozzle having a rapidly diverging open interior, with the outer end having radial web portions extending thereacross, a supply fitting threaded into the central portion of the web portion of the outer end of the burner, a plate adjustable on the supply fitting for controlling the supply of air to the burner, the inner end of the fitting being provided with a restricted orifice for directing combustion gas toward the inner end of the burner and thereby drawing air through the outer end of such burner, a flange mounted on the burner and projecting laterally beyond the lateral dimensions of the inner end thereof and provided with a cut out portion for receiving pilot light gas supply and control elements, a laterally extending lug on the nozzle projecting radially in the same direction from the tubular nozzle as said cut out, upon which a bracket may be mounted for a pilot light for projecting a flame toward the inner end of said nozzle and upon which a flame responsive structure controlled by said pilot light may be mounted.

2. A burner unit for application to a furnace comprising a tubular nozzle including an inner end having a restricted discharge opening, an intermediate portion of the nozzle having a restricted cross-sectional shape and the outer end portion of the nozzle having a rapidly diverging open interior, means to secure a supply fitting to the outer end of said nozzle, means to control the supply of air to said burner, the inner end of the fitting being provided with a restricted orifice for directing combustion gas toward the inner end of the burner and thereby drawing air through the outer end of such burner, a flange mounted on the burner and projecting laterally beyond the lateral dimensions of the inner end thereof and provided with a cut out portion for receiving pilot light gas supply and control elements, a laterally extending lug on the nozzle projecting radially in the same direction from the tubular nozzle as said cut out, upon which a bracket may be mounted for a pilot light for projecting a flame toward the inner end of said nozzle and upon which a flame responsive structure controlled by said pilot light may be mounted.
